United States Patent Office

Des. 195,300
Patented May 28, 1963

195,300

HANGER FOR PACKAGES OR THE LIKE

Joseph M. Margulis, % Jiffy Enterprise Inc.,
150 N. 13th St., Philadelphia, Pa.

Filed Oct. 5, 1962, Ser. No. 72,005

Term of patent 14 years

(Cl. D17—12)

Fig. 1.

Fig. 5.

Fig. 2.

Fig. 3.

Fig. 4.

Fig. 6.

FIGURE 1 is a side elevational view of a hanger for packages or the like showing my new design in its relationship to a wall surface shown in broken lines for illustrative purposes only;

FIGURE 2 is an edge elevational view as seen from the left of FIGURE 3;

FIGURE 3 is a side elevational view of the side opposite FIGURE 1;

FIGURE 4 is an edge elevational view as seen from the right of FIGURE 3;

FIGURE 5 is a top plan view of FIGURE 3; and FIGURE 6 is a bottom plan view thereof.

I claim:

The ornamental design for a hanger for packages or the like, substantially as shown and described.

References Cited in the file of this patent

UNITED STATES PATENTS

139,972	Redfern -----	June 17, 1873
1,081,549	Mulon -----	Dec. 16, 1913